United States Patent

Des. 242,060

Patented Oct. 26, 1976

242,060

LACE FABRIC

Martha M. Johns, Wilmington, Del., assignor to E. I. du Pont de Nemours & Company, Wilmington, Del.

Filed Feb. 13, 1974, Ser. No. 442,159

Term of patent 14 years

Int. Cl. D5—02

U.S. Cl. D47—6 B

FIG. 1

FIG. 2

FIG. 1 is a plan view of a lace fabric showing my new design which is repeated in the vertical and horizontal directions; the design is shown over a dark background for purposes of illustration; and

FIG. 2 is an enlarged fragmentary view of the repeat unit thereof.

I claim:

The ornamental design for a lace fabric, substantially as shown and described.
